UNITED STATES PATENT OFFICE.

EDWIN F. GUTH, OF ST. LOUIS, MISSOURI, ASSIGNOR TO LUMINOUS UNIT CO., OF ST. LOUIS, MISSOURI, A CORPORATION OF MISSOURI.

DESIGN FOR A REVOLVING TRAY.

50,723.

Specification for Design.

Patented May 8, 1917.

Application filed March 17, 1917. Serial No. 155,620. Term of patent 14 years.

To all whom it may concern:

Be it known that I, EDWIN F. GUTH, a citizen of the United States, residing at St. Louis, in the State of Missouri, have invented a new, original, and ornamental Design for a Revolving Tray, of which the following is a specification, reference being had to the accompanying drawing, forming part thereof.

The figure is a perspective view of a revolving tray, showing my new design.

I claim:

The ornamental design for a revolving tray, as shown.

EDWIN F GUTH.
